(57) **CLAIM**

The ornamental design for a holder for a digital dental x-ray sensor, as shown and described.

DESCRIPTION

FIG. 1 is a front perspective view of a holder for a digital dental x-ray sensor, showing our new design;

FIG. 2 is a rear perspective view of the holder for a digital dental x-ray sensor of FIG. 1;

FIG. 3 is a front elevational view of the holder for a digital dental x-ray sensor shown in FIG. 1;

FIG. 4 is a rear elevational view of the holder for a digital dental x-ray sensor shown in FIG. 1;

FIG. 5 is a side elevational view of the holder for a digital dental x-ray sensor of FIG. 1;

FIG. 6 is a side elevational view of the holder for a digital dental x-ray sensor of FIG. 1 and showing the side opposite that of FIG. 5;

FIG. 7 is a top plan view of the holder for a digital dental x-ray sensor of FIG. 1; and,

FIG. 8 is a bottom plan view of the holder for a digital dental x-ray sensor of FIG. 1.

1 Claim, 8 Drawing Sheets
